United States Patent Office.

JOHN L. ARMS, OF ST. LOUIS, MISSOURI.

Letters Patent No. 100,101, dated February 22, 1870.

IMPROVED RAILROAD-SWITCH.

The Schedule referred to in these Letters Patent and making part of the same.

To all whom it may concern:

Be it known that I, JOHN L. ARMS, of St. Louis, in the county of St. Louis, and State of Missouri, have made certain new and useful Improvements in Railroad-Switch; and I do hereby declare that the following is a full and true account thereof, reference being had to the accompanying drawings and to the letters of reference marked thereon.

The object of this invention is to enable an operator on the train of cars to operate the switch, and the arrangement is, moreover, such that the operator may, by placing the operating bar in proper position, cause a misplaced switch to be thrown into line, and thus prevent running off the track. For said purposes, the nature of this invention is in the use of a series of hinged levers to operate shafts and other intermediate devices, by which the switch-bar is thrown and the switch thus moved.

To enable those herein skilled to make and use said improved invention, I will now more fully describe the same, referring to the accompanying

Figure 1 as a plan; to

Figure 2 as a sectional elevation; to

Figure 3 as an end view.

In said figures—

A represents the main line of track;

B, the side track; and

C is the switch-rail, pivoted at ends as usual and commonly done, and operated by the switch-bar D to connect either with the line A or the track B, in the manner now usual and generally indicated in the said figures.

In order that said switch-rails may be thrown by the operator from the car X, I arrange the slide x, moved longitudinally by the operator by the pivoted hand-lever x', said parts being properly secured on, say, a rear car of a train and on the locomotive engine.

The slide thus placed operates the knee-levers E E' and F F', placed at the side of the track, and connecting with the shafts G. As the car passes by the said levers, the slide x acts to depress one of said lever devices, and thus to turn said shaft, it being in the discretion of the operator which of said devices shall be acted upon, and the movement of the switch being thus determined.

The levers E and E' and F and F' are linked together, the levers E and F being permitted to slide in stirrup supports e and f.

By the operation of the shafts G, the arms g, and through the intermediate connecting-rods H, the bell-crank lever I is operated, and herefrom, by the connecting-rod K, the switch-bar D is thrown to operate the switch as desired. Said devices for communicat-

ing motion from said shafts G to the switch-bar being dependent upon the place and general arrangement of parts, and being readily adapted by an ordinary mechanician. All said devices are properly supported and secured usually upon ties.

In order that the switch-bar D may not be moved when not desired by concussion of passing trains, I arrange the locking-block d. This is of triangular form, and secured by the pivot d' to said switch-bar. Said block abuts at its lower edge against the check-plate d'', secured upon the stand or frame D', to which the switch-bar is pivoted, at d'. By arranging said pivot d' on the tie D'', the connecting-rod D' from said switch-bar to the rails C being slightly above, it will be seen that the block d acts at a great leverage, to prevent concussions upon the rails C from operating said switch-bar. On the other hand, the connecting rod K being somewhat above the attachment of the block d, the power transmitted through said connecting-rod is advantageously used to move the switch-bar D and its locking-block d. The arrangement is, therefore, such that the operator may readily move the switch-bar and switch by the lever x' and slide x, while at the same time the switch is well secured against any movement which might be caused from the switch-rails C themselves.

If deemed advisable, a spring may be used to hold the locking-block d in the position given thereto in its operation, as heretofore described.

The knee-levers E E' and F F' will be placed so that trains approaching the switch from either direction may readily operate the same.

As a further security, a locking-block similar to d may be attached to each of the switch-rails C, so that in moving the said rails they will be lifted up slightly as the block is turned; then, as the effect of a train is to hold down the rails C, the blocks d would give additional security against improper movement of said switch-rails.

Having thus fully described my said invention,

What I claim is—

1. The arrangement of the slide x with the levers E E' F F', the shaft G, arm g, and connecting devices H I K, with the switch-levers and switch-rails, substantially as and for the purpose set forth.

2. The switch-bar D, pivoted at d', when combined with the locking-block d and check-plate d'', substantially as and for the purposes set forth.

JOHN L. ARMS.
